United States Patent Office

Des. 198,677
Patented July 21, 1964

198,677

SERVICE CART

Glen A. Johnson, % Stant Manufacturing Co., Inc.,
Connersville, Ind.

Filed Dec. 18, 1963, Ser. No. 77,850

Term of patent 14 years

(Cl. D14—3)

Fig. 1.

Fig. 2.

Fig. 3.

Fig. 4.

Fig. 5.

FIG. 1 is a front, perspective view of a service cart embodying my new design;

FIG. 2 is a rear perspective view thereof with the storage door shown in open position;

FIG. 3 is a side elevational view taken from the left of FIG. 1;

FIG. 4 is a top plan view thereof; and

FIG. 5 is a rear elevational view like FIG. 2 but with the storage door shown in closed position.

I claim:

The ornamental design for a service cart, as shown and described.
